(57) CLAIM

The ornamental design for an address display, as shown and described.

DESCRIPTION

FIG. 1 is a front perspective view of an address display showing the new design;

FIG. 2 is a front elevational view thereof;

FIG. 3 is a rear elevational view thereof;

FIG. 4 is a side elevational view, of either the right or left side, thereof;

FIG. 5 is a top plan view thereof; and,

FIG. 6 is a bottom plan view thereof.

Any broken line illustration of environmental structure in the drawings is not part of the design sought to be patented.
